US00D640473S

(12) **United States Design Patent**
Bonilla et al.

(10) **Patent No.:** **US D640,473 S**
(45) **Date of Patent:** **** Jun. 28, 2011**

(54) **PAPER PRODUCT**

(75) Inventors: **Alejandro Javier Bonilla**, Cincinnati, OH (US); **Donn Nathan Boatman**, Union, KY (US)

(73) Assignee: **The Procter & Gamble Company**, Cincinnati, OH (US)

(**) Term: **14 Years**

(21) Appl. No.: **29/333,468**

(22) Filed: **Mar. 10, 2009**

(51) LOC (9) Cl. **05-02**

(52) U.S. Cl. **D5/58**

(57) **CLAIM**

The ornamental design for a paper product, as shown and described.

DESCRIPTION

The Sole FIGURE is a top plan view of the paper product, it being understood that the outer perimeter depicts the boundaries of one repeat unit of the claimed design and indicates that the design may continue in one or more directions. The design repeats uniformly throughout the length and width of the paper product. the broken lines in the figures form no part of the claimed design.
